UNITED STATES PATENT OFFICE.

JOSHUA R. EDDY AND RICHARD F. HADLEY, OF SLICKER, WEST VIRGINIA, ASSIGNORS OF ONE-THIRD TO SAID EDDY, ONE-HALF TO PERLEY S. SMITH, AND ONE-SIXTH TO HARIET E. SMITH, OF SLICKER, WEST VIRGINIA.

CASING-HEAD FOR OIL-WELLS.

No. 822,930.

Specification of Letters Patent.

Patented June 12, 1906.

Application filed February 16, 1906. Serial No. 301,410.

To all whom it may concern:

Be it known that we, JOSHUA R. EDDY and RICHARD F. HADLEY, citizens of the United States, residing at Slicker, in the county of 5 Tyler and State of West Virginia, have invented a new and useful Casing-Head for Oil-Wells, of which the following is a specification.

This invention relates to casing-heads for 10 oil-wells, and has for its object to provide improved means for catching the flow of oil when the operating mechanism is withdrawn from the well-casing.

A further object of the invention is to provide 15 a casing-head having a cut-off valve pivotally mounted therein and movable to operable position when the tools are withdrawn, thereby to deflect the flow of oil through a series of discharge-openings into a suitable oil-saver or other receptacle designed to receive 20 the same.

A still further object is to generally improve 25 this class of devices so as to add to their utility and durability, as well as to reduce the cost of manufacture.

With these and other objects in view the invention consists in the construction and novel combination and arrangement of parts hereinafter fully described, and illustrated in 30 the accompanying drawings, it being understood that various changes in form, proportions, and minor details of construction may be resorted to within the scope of the appended claims.

In the accompanying drawings, forming a 35 part of this specification, Figure 1 is a side elevation of a casing-head constructed in accordance with my invention. Fig. 2 is a longitudinal sectional view taken on the line 2 2 40 of Fig. 3. Fig. 3 is a similar view taken on the line 3 3 of Fig. 1.

Similar numerals of reference indicate corresponding parts in all the figures of the drawings.

The device consists of a tubular body portion 45 comprising a relatively stationary section 5 and a movable section 6, said sections being provided with laterally-extending reinforcing-flanges 7 having coincident openings 50 formed therein for the reception of clamping-bolts 8. One end of the body portion is ex-

tended to form an annular flange 9, having set-screws 10 threaded therein for engagement with an oil-saver or other suitable receptacle designed to receive the oil, while the opposite end of said body portion is threaded at 11 for connection with the adjacent section of the well-casing.

The pivoted section 6 is provided with a reduced extension or tongue 12, the end of which is curved or rounded, as indicated at 13, and seated in a correspondingly-shaped socket 14, formed in an enlargement 15 on the stationary section 5, the sections being pivotally united by means of a bolt 16, passing through the enlargement and engaging the tongue, as shown.

The interior walls of the movable section 6 are provided with a circular depression or recess 18, which forms a seat for a valve 19 when the latter is in open position, said valve being adapted to engage an annular stop-collar or flange 20, extending inwardly from the walls of both sections when the valve is in closed or operative position.

The valve 19 is preferably circular in form and provided with a reduced shank 21, the end of which is seated in a recess 22, communicating with the recess 18 and rigidly secured to a rock-shaft 23, journaled in a suitable bearing-plate 24, fastened to the movable section 6. The rock-shaft is extended a short distance beyond the plate 24 and provided with an operating-handle 25, by means of which the valve may be moved to operative and inoperative positions.

The walls of the stationary and movable sections are provided with a plurality of threaded discharge-openings 26, through which the oil is discharged when the pump-operating mechanism is withdrawn and the valve 19 is in closed position, the oil being preferably conducted through suitable pipes threaded in the openings 26 and communicating with the oil-saver or other suitable receptacle designed to receive the same.

When the pump is in operation, the valve 19 is in open or inoperative position, as shown by dotted lines in Fig. 3 of the drawings, thereby permitting free vertical movement of the sucker-rod or operating-tools within the well-casing. When the operating mech-

- anism or tools are withdrawn, however, the valve is moved to closed position in engagement with the stop-collar by turning the operating-handle to the position shown in full lines in Fig. 3, thereby cutting off the flow of oil at the top of the casing and deflecting the same through the discharge-opening, the oil being conducted through suitable pipes to an oil-saver or other receptacle, as before stated.
- 15 5 It will thus be seen that the flow of oil, which usually occurs when the operating-tools are withdrawn from the casing, is effectually saved, thus enabling the operator to utilize the entire output of the well.
- 15 10 By having the casing-head formed in sections, one of which is movable laterally to open position, said movable section may be swung outwardly by releasing the clamping-bolts 8 to thereby permit the ready insertion
- 20 15 and removal of the cut-off valve and also to permit the removal of any accumulations of foreign matter within the head.
- Having thus described the invention, what is claimed is—
- 25 20 1. A tubular-casing head comprising stationary and movable sections provided with discharge-apertures, and a valve carried by one of said sections and adapted to close the adjacent end of the casing-head.
- 30 25 2. A tubular-casing head comprising stationary and movable sections having discharge-apertures formed in the side walls thereof, and a valve carried by the movable section for closing the adjacent end of the casing-head.
- 35 30 3. A tubular-casing head comprising stationary and movable sections provided with lateral discharge-apertures, a rock-shaft carried by the movable section and provided with an operating-handle, and a valve se-
- cured to the rock-shaft and adapted to close the adjacent end of the casing-head.
4. A tubular-casing head comprising stationary and movable sections provided with lateral discharge-apertures, a seating-recess 45 formed in the movable section, a valve seated in said recess and adapted to close the adjacent end of the casing-head, and a weighted lever secured to the valve for operating the same.
5. A tubular casing comprising stationary and movable sections provided with lateral discharge-apertures, one of said sections being provided with a seating-recess having an opening communicating therewith, a valve 55 seated in the recess and provided with a reduced shank movable between the walls of said opening, a rock-shaft secured to the valve and provided with a handle for actuating the valve to close one end of the casing-head, and 60 means for clamping the sections together.
6. A tubular-casing head comprising a stationary section having a socket formed therein, a movable section provided with a reduced extension pivotally mounted within the 65 socket, a valve pivoted to the movable section and adapted to close the adjacent end of the casing-head, there being a plurality of discharge-apertures formed in the walls of said sections and means for clamping the sections together.
- 70 In testimony that we claim the foregoing as our own we have hereto affixed our signatures in the presence of two witnesses.

JOSHUA R. EDDY.
RICHARD F. HADLEY.
